UNITED STATES PATENT OFFICE.

HERMAN WALTHER, OF TOLEDO, OHIO.

DESIGN FOR A PUMP-BARREL.

SPECIFICATION forming part of Design No. 88,859, dated January 8, 1901.

Application filed December 7, 1900. Serial No. 39,102. Term of patent 14 years.

To all whom it may concern:

Be it known that I, HERMAN WALTHER, a citizen of the United States, residing at Toledo, in the county of Lucas and State of Ohio, have invented and produced a new and useful Design for Pump-Barrels, of which the following is a specification.

My invention relates to new and useful designs for pump stocks or barrels, of which the following is a specification, reference being had to the accompanying drawings, forming a part thereof, in which—

Figure 1 is a perspective of my pump-barrel. Fig. 2 is a horizontal section on the line 15 2 2, Fig. 1.

Like numerals of reference denote like parts in the different views of the drawings.

The principal part of the pump-barrel is octagonal in cross-section and is designated 20 by the numeral 1. A collar 2, which has a sloping upper face, is formed on the member 1 about centrally thereof. The lower end 3 of the barrel is cylindrical in form. A spout

4 juts out from the side of the member 1 at a point above the collar 2. Apertured ears or 25 lugs 5 are formed on the upper end of the barrel, and a cover 6, having an inclined upper face which is provided with a knob 7, surrounds the whole structure and completes my design.

The material or essential features of my design are a barrel having octagonal and cylindrical portions and a cover for the same surrounded by a knob.

Having thus described my invention, what 35 I claim as new, and wish to secure by Letters Patent, is—

The design for a pump-barrel, substantially as shown and described.

In testimony whereof I have hereunto set 40 my hand in presence of two subscribing witnesses.

HERMAN WALTHER.
